UNITED STATES PATENT OFFICE

134,578

DESIGN FOR A MOTORCYCLE

Stephen du Pont, Wilbraham, Mass., and Benjamin B. du Pont, Montchanin, Del., assignors to Indian Motorcycle Company, Springfield, Mass., a corporation of Massachusetts

Application July 23, 1942, Serial No. 107,660

Term of patent 14 years

To all whom it may concern:

Be it known that we, Stephen du Pont, a citizen of the United States, residing at Wilbraham, in the county of Hampden, and State of Massachusetts, and Benjamin B. du Pont, a citizen of the United States residing at Montchanin, in the county of New Castle, and State of Delaware, have invented a new, original, and ornamental Design for a Motorcycle, of which the following is a specification, reference being had to the accompanying drawing, forming a part thereof.

Referring to the drawing:

Fig. 1 is a side elevational view of a motorcycle, showing our new design; and

Fig. 2 is a perspective view of the combined saddle and fuel tank shown in Fig. 1, the dotted lines being omitted for convenience in illustration.

The essential and characterizing features of our design reside in the portions shown in full lines.

We claim:

The ornamental design for a motorcycle, as shown and described.
